FIELDER I. HISS, OF SPRINGFIELD, OHIO, ASSIGNOR TO ROBBINS & MYERS, INC., OF SPRINGFIELD, OHIO, A CORPORATION OF OHIO

SHORT-CIRCUITING DEVICE

Application filed June 14, 1929. Serial No. 371,015.

This machine relates to short circuiting devices for electric motors and it particularly relates to that type of short circuiting device employing a plurality of centrifugally operated weights arranged in an annular series and adapted to make a direct contact with the commutator bars.

The object of my invention is to provide a simple and effective arrangement whereby the weights after contact with the commutator bars may have an additional sliding movement on the bars for the purpose of preserving good contact surfaces.

In the accompanying drawings:

15 Fig. 1 is a view partly in side elevation and partly in longitudinal section of a short circuiting device embodying my improvements, the short circuiting elements being in inoperative position.

20 Fig. 2 is a view similar to the sectional portion of Fig. 1 showing the short circuiting elements in operative position.

Fig. 3 is a section on the line 3—3 of Fig. 1.

25 Fig. 4 is a longitudinal section showing a modification.

Referring to the drawings, 1 represents the shaft of the motor, 2 the core of the commutator and 3 the commutator bars having their outer ends provided with inclined contact surfaces 3'. Slidably mounted upon the motor shaft is a sleeve 4 having fast thereto a cup-shaped disk 5 within which are mounted the short circuiting elements, each consisting of a plate or slug 6, the outer end of which is provided with a rounded ear 7 to form a pivot and with a rounded nose 8 to form a contact point, the bend in the disk serving as a fulcrum for the weights and being rounded to conform to the rounded form of the pivot ears. These plates or slugs are arranged in an annular series about the sleeve and are held in their normal inoperative position by a ring or washer 9 which is pressed in yielding engagement with the outer edges thereof by a coil spring 10 which is confined between the ring 9 and a washer 11 fixed against endwise movement on the sleeve 4.

Axial movement of the sleeve 4 on the motor shaft is resisted by a conical spiral spring 12, housed in a cup-shaped disk 13 secured

to the end of the sleeve 4 and confined by a disk 14 mounted against the shoulder of a collar 15 fixed to the motor shaft.

In operation, when the motor has acquired a predetermined speed, the weights 6 swing outwardly against the compression of the spring 10, and make contact with the commutator bars. Increased speed of the motor then causes a further outward movement of the weights against the compression of the spring 12, this additional movement causing the contact noses 8 to impart the desired wiping action upon the inclined contact surfaces of the commutator bars. By this construction the action of each spring is entirely independent of the other and allows the weights to first make contact with the commutator bars and then have an additional wiping movement upon the bars.

In Fig. 4 there is shown a modification in the form of the spring which controls the axially movable sleeve. In this case the spring is a coil spring, as indicated at 16 which is placed mainly in a large bore or recess 17 in the sleeve 4' and is confined between the inner wall of the recess and a nut 18 threaded on the motor shaft.

In order to prevent the weights 6 from binding, I have divided the series of weights into groups separated by partitions 19 which are carried by the cup-shaped disk 5; these partitions being in the present case four in number which are immovably secured to the disks in equally spaced relation.

Having thus described my invention, I claim:

1. In a short circuiting device for electric motors, a shaft, a sleeve axially movable upon said shaft, an annular series of weights confined on said sleeve movable outwardly by centrifugal force to contact with the commutator bars, a spring on said sleeve opposing the initial movement of said weights, and a second spring on said shaft opposing axial movement of said sleeve due to further outward movement of the weights, but which is ineffective to oppose the initial movement of the weights.

2. In a short circuiting device for electric motors, an axially movable sleeve arranged

on the shaft of the motor, a cup-shaped rotating disk connected with said sleeve, an annular series of weights on said sleeve having their outer ends fulcrumed on said disk, a spring on said sleeve to oppose the initial outward movement of said weights by centrifugal force, and a second spring on the shaft of the motor to oppose axial movement of said sleeve due to further outward movement of the weights, but which is ineffective to oppose the initial movement of the weights.

3. In a short circuiting device for electric motors, a motor shaft, a sleeve axially movable thereon, a disk mounted on the outer end 15 of said sleeve having an annular flange, and an annular series of weights about said sleeve, the outer end of each weight having a projection forming a pivot fulcrumed on the outer flanged portion of said disk, a spring 20 on said sleeve tending to oppose the initial outward swinging movement of said weights by centrifugal force, and a second spring carried by said shaft and bearing on said sleeve to oppose axial movement of said sleeve but 25 permitting the contact points of said weights to have a limited sliding movement upon the commutator bars due to further outward movement of the weights, but which is ineffective to oppose the initial movement of the 30 weights.

4. In a short circuiting device for electric motors, a shaft, a series of commutator bars mounted thereon having inclined contact surfaces, a sleeve axially movable upon said shaft, a spring on said shaft bearing against said sleeve, a housing carried by said sleeve, an annular series of weights about said sleeve and having their outer ends fulcrumed on said housing, contact noses also on the outer 35 ends of said weights adapted when said weights are thrown outwardly by centrifugal force to contact the inclined surfaces of said commutator bars, a spring on said sleeve to oppose the initial outward movement thereof, said first mentioned spring permitting limited axial movement of said sleeve after said 40 weights have made contact with said bars due to further outward movement of the weights, but which is ineffective to oppose the initial 45 movement of the weights.

In testimony whereof I have hereunto set my hand this 27th day of May, 1929.

FIELDER I. HISS.
